Primary Examiner — Amy C Wierenga(74) *Attorney, Agent, or Firm* — John Wood; Wood Patent Law(57) **CLAIM**

The ornamental design for a fluid line connection shell, as shown and described.

DESCRIPTION

FIG. 1 is a top front perspective view of a fluid line connection shell showing our new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines shown represent unclaimed subject matter and form no part of the claimed design.
